UNITED STATES PATENT OFFICE.

AUGUSTO DINA, OF JERSEY CITY, NEW JERSEY, ASSIGNOR TO INTERNATIONAL PROJECTOR CORPORATION, OF NEW YORK, N. Y., A CORPORATION OF DELAWARE.

DESIGN FOR A BASE FOR A MOTION-PICTURE MACHINE.

Application filed April 18, 1928. Serial No. 26,376. Term of patent 14 years.

To all whom it may concern:

Be it known that I, AUGUSTO DINA, a citizen of the United States, residing at Jersey City, in the county of Hudson and State of New Jersey, have invented a new, original, and ornamental Design for Base for Motion-Picture Machine, reference being had to the accompanying drawing, forming part thereof.

Fig. 1 is a plan view of a base for a motion picture machine showing my new design:

Fig. 2 is a side elevation thereof;

Fig. 3 is a rear elevation; and

Fig. 4 is a front elevation.

I claim:

The ornamental design for a base for a motion picture machine, as shown.

AUGUSTO DINA.
